UNITED STATES PATENT OFFICE.

BERTRAND L. GEORGE, OF METHUEN, MASSACHUSETTS.

LAMP-GUARD.

1,188,923.

Specification of Letters Patent. Patented June 27, 1916.

Application filed July 26, 1915. Serial No. 41,823.

To all whom it may concern:

Be it known that I, BERTRAND L. GEORGE, a citizen of the United States, residing at Methuen, in the county of Essex and State 5 of Massachusetts, have invented a new and useful Lamp-Guard, of which the following is a specification.

This invention relates to a guard for an incandescent electric lamp, and the principal 10 objects of the invention are to provide a guard which in addition to protecting the lamp itself, extends entirely around the lamp socket and offers protection for the same throughout the entire length of the 15 socket; to provide a construction in which the lamp socket is yieldingly held by the guard itself in position in the neck of the guard so as to hold the lamp in central position and prevent motion of the guard longitudinally and yet permit of the insertion and 20 removal of the socket by pressure in a longitudinal direction; to provide means for holding the socket in such form that when the socket is removed this means can be bent 25 back and forth readily to adjust its gripping tension; and to provide a construction in which the guard is formed of wire and specifically of a series of wires arranged longitudinally and so constructed that when 30 used on a key socket the key will slip into position in the guard between the wires when the lamp is moved into place longitudinally.

The invention also involves a yielding connection at the end of the guard for receiving 35 the connecting wires and permitting the suspension of the guard in a yielding manner and also the provision of a stand in connection with the guard in which the lamp can 40 be held in upright position.

Further objects and advantages of the invention will appear hereinafter.

Reference is to be had to the accompanying drawings in which—

45 Figure 1 is a side view of a lamp guard constructed in accordance with this invention, and Fig. 2 is a similar view of a modified form.

In the form shown in Fig. 1 the guard 50 consists of a wire frame A formed of longitudinal wires a arranged in a circle and connected together by two circular wires a' and the guard is provided with an open end. These wires a are bent inwardly beyond one circular wire a' so as to form the neck B concentric with the frame A and at

the end thereof. The wires a are shown as arranged in pairs, certain pairs extending to the end of the neck B where they are secured together by a circular wire a^2 at the 60 end. Each alternate pair of wires a in this case are used for a different purpose. They are contracted inwardly so as to form a part of the neck, but they do not extend to the wire a^2 , but on the contrary are doubled over 65 on themselves at a point part way between the ends of the neck. In other words, two of these wires are integral with each other and bent at a point a^3 . These wires that are bent at this point therefore form a projecting 70 resilient tongue which can be bent back and forth to adjust its position. These tongues are provided with projections a^4 extending inwardly for the purpose of engaging in a groove c in a lamp socket C. In 75 the form shown in Fig. 1 this socket is shown as of the porcelain type. The lamp D is shown mounted in this socket. At the end of the neck B is a spring E which surrounds the conducting wires or cable, having 80 a collar e for this purpose. This offers a means by which the guard can be held yieldingly so as to reduce the effects of any shocks to which it may be subjected.

It will be seen from what has been said 85 that the lamp can be inserted in the guard by forcing it inwardly in a longitudinal direction until the projections a^4 enter the groove c and that it is then held yieldingly but firmly in that position and although 90 there is no danger of accidental displacement, yet it can be drawn out longitudinally. It will be seen also that the tongues a^3 can be bent out or in to adjust their position and the degree of pressure which they put 95 upon the socket. In the form shown three of these tongues are present and they hold the socket centrally and thus also hold the lamp in central position. The other end of the socket substantially engages the neck of 100 the guard so as to prevent its getting out of alignment. It will be seen also that the wires e are so arranged that when the socket is being put into place the key e' of the socket will slip in between two of the wires 105 and move substantially to the end of the space between them.

In the form shown in Fig. 2 substantially the same principles apply, except that the wires of the neck B' are secured at the end 110 of the neck by contracting the wires and placing a ring B^2 around the same to hold

them in position and these wires are extended beyond this ring and then flare out to form a stand F on which the whole device can be supported. In this case also a metallic socket C' is shown in which there is no groove around the same, but which is provided with a shoulder C² and the tongues A³ are correspondingly shaped, the purpose being the same as in the other case.

10 Although I have illustrated and described only two embodiments of the invention and shown it as arranged for supporting only two kinds of lamp sockets, I am aware of the fact that many other modifications can be made in the invention and that it can be adapted for supporting lamp sockets of other shapes without departing from the scope of the invention as expressed in the claims. Therefore I do not wish to be limited in 15 these respects, but

What I do claim is:—

1. The combination with an incandescent electric lamp and socket, of a guard therefore comprising a wire frame adapted to 25 surround the lamp and having a central contracted substantially rigid neck at one end constituting a complete cylinder terminating in a circular end wire so as to form a comparatively rigid handle for manipulating it, and means for engaging the socket and holding the socket centrally, whereby the lamp is held centrally in the frame and also for holding the socket against longitudinal motion, said neck surrounding and protecting the socket substantially throughout its 30 length.

2. The combination with an incandescent electric lamp and socket, of a guard therefore comprising a frame formed with a plurality of longitudinal wires arranged in a 40 circle and adapted to surround the lamp, said wires being contracted at the end of the frame so as to form a cylindrical contracted neck, certain of said wires extending to the 45 end of said neck and being secured at the end, and others of said wires terminating at a point between the end of the neck and the end of the body of the guard so as to form resilient tongues having projections 50 thereon for engaging the lamp socket.

3. As an article of manufacture, a lamp guard comprising a frame having a body for receiving an incandescent electric lamp and formed with a series of longitudinal wires 55 contracting at the end of the body to form a cylindrical neck or longitudinal continua-

tion of said wires and provided with integral wire means located between the ends of said neck for resiliently holding a lamp socket therein and preventing its moving 60 out of position.

4. As an article of manufacture, a lamp guard comprising a cylindrical body having a plurality of longitudinal wires constituting its main portion, said wires being bent 65 inwardly at the end of said main portion and extending longitudinally therefrom in the form of a cylindrical neck for receiving a lamp socket, certain pairs of said wires adjacent to each other being formed integrally with each other and doubled over 70 within the circumference of said neck to form resilient tongues for holding the lamp socket therein, said tongues being provided with inward projections for engaging the 75 lamp socket.

5. As an article of manufacture, a wire lamp guard comprising a frame having a body for receiving an incandescent electric lamp having a cylindrical neck for holding 80 a lamp socket therein, and a member on the end of said neck consisting of a spring wire coiled on itself for surrounding the conductors connected with the socket.

6. As an article of manufacture, a lamp 85 guard comprising a frame having a body for receiving an incandescent electric lamp and formed with a series of longitudinal wires contracted at the end of the body to form a neck for holding a lamp socket therein, said 90 longitudinal wires at the end of the neck being contracted at the end of the neck and having a ring surrounding them to hold them in position, and then flaring away from each other to form a base for supporting 95 the guard.

7. As an article of manufacture, a lamp guard comprising a frame having a body for receiving an incandescent electric lamp and formed with a series of wires contracted 100 at the end of the body to form a neck for holding a lamp socket therein, said neck being contracted at the end and then flaring away to form a base for supporting the 105 guard.

In testimony whereof I have hereunto set my hand, in the presence of two subscribing witnesses.

BERTRAND L. GEORGE.
